UNITED STATES PATENT OFFICE.

FRANZ BÜRGER, OF MANNHEIM, GERMANY, ASSIGNOR TO THE FIRM OF HEINRICH LANZ, OF MANNHEIM, GERMANY.

SUPERHEATER AND ECONOMIZER FOR HORIZONTAL SMOKE-TUBE BOILERS.

1,143,501.

Specification of Letters Patent. Patented June 15, 1915.

Application filed February 27, 1914. Serial No. 821,595.

To all whom it may concern:

Be it known that I, FRANZ BÜRGER, citizen of the German Empire, residing at 33 Heinrich Lanz strasse, Mannheim, Germany, have invented certain new and useful Improvements in Superheaters and Economizers for Horizontal Smoke-Tube Boilers, of which the following is a specification.

10 This invention relates to the arrangement of the superheater and economizer tubes within the smoke box of horizontal smoke-tube boilers.

One object of the present invention consists in accommodating both the system of superheater tubes and the system of economizer tubes within the smoke box and in arranging them within a single transverse zone within said smoke box.

20 A further object of the present invention consists in continuing the annular smoke flues downwardly in such manner as to provide a plurality of spaces through which the furnace gases pass, these spaces being 25 provided with corresponding controlling valves or dampers and serving for the reception of the superheater and economizer tubes.

In order that the present invention may 30 be more clearly understood reference is made to the accompanying drawings illustrating certain embodiments of the invention by way of example.

Figure 1 is a vertical section through the 35 smoke box of the boiler of a semi-portable engine having my invention applied. Fig. 2 is a similar view to Fig. 1 showing a slight modification thereof. Fig. 3 is a longitudinal vertical section through a semi-portable 40 engine having the superheater and economizer tubes arranged in the manner shown in Fig. 1.

In the drawings a superheater system is 45 illustrated of the type described in the specification of United States Patent #934,151 comprising sinuous tubes running parallel to the boiler axis.

According to the present invention instead of arranging the superheater tubes 50 over their whole length concentric with the boiler around the inner shell as has already been proposed, the lower part of the superheater beneath the horizontal central plane is according to Figs. 1 and 3 continued vertically downwardly so that between the two

lower ends of the superheater a space is left for the reception of the very compact economizer.

According to Fig. 2 the concentric part of the superheater is somewhat shorter than 60 in the arrangement described in the aforesaid United States specification and only lengthened in the axial direction sufficient to provide the necessary heating surface. Directly beneath the superheater is arranged 65 the economizer whose tubes are of the same length as the superheater. The smoke flue is in this case continued vertically downwardly from the lower end of the superheater and between the two halves of the 70 economizer is left a space to receive the ash particles entrained by the furnace gases.

On the drawings *a* designates the annular superheater space within which the superheater tubes are arranged, *b* designates the 75 end tube plate, *c* the economizer spaces within which the economizer tubes are arranged, *d* the space between the two halves of the economizer and *a'* the down-take flue for the furnace gases.

In Figs. 1 and 3 the flue plates 1 and 3 form the inner shell of the smoke flues while 2, 4 and 5 designate controlling valves or dampers, the valves 2 simultaneously constituting part of the inner shell. By means of the valves 2, 4 and 5 either the superheater alone or the economizer alone or both may be simultaneously traversed by the furnace gases or cut off therefrom. For the purpose of enabling both systems of tubes to be run 90 out they are preferably mounted upon rollers *f*, each system being mounted independently upon rollers as in Figs. 1 and 3 or in common with each other as in Fig. 2.

When both systems of tubes are put in 95 communication with the furnace gases as will usually be the case, the gases will flow both through the superheater and the economizer in the opposite direction to the flow of the feed water in the economizer and the 100 flow of the saturated steam in the superheater, first passing through the superheater and then through the economizer. The transit from the superheater to the economizer takes place directly, that is to say, 105 without intermediate loss of heat. The whole arrangement results in uniformity of the plant requiring the smallest possible floor surface and without requiring variation of the space available for locomotives, 110

semi-portable engines and the like of this type, while, moreover, being of extremely small weight and readily capable of access for cleaning purposes.

5 As shown in Fig. 3 the saturated steam is supplied from the horizontal boiler *g* by way of the pipe *h* to the lower tubular header *i* of the superheater tubes *k*. In order to prevent confusion, the superheater 10 tubes are shown broken away. The superheater tubes pass in a sinuous course between the outer shell of the smoke box and the inner shell plates 1 and terminate above in a tubular header *l* from which the steam 15 is supplied by the pipe *m* to the steam engine *n*. The feed water is supplied to a tubular header *o* and passes through the economizer tubes *p* in a sinuous course to the tubular header *q* from which it is supplied 20 to the boiler *g*. The gases from the furnace chamber *r*, after passing through the smoke tubes *s* of the boiler (only a few of which are shown for the sake of simplicity), enter the interior of the smoke box 25 *t* and are drawn upwardly, dividing in the upper part of the smoke box and passing downwardly on both sides between the outer shell and the inner shell plates 1, heating the superheater tubes on their way. The 30 gases then turn inwardly and pass downwardly through the economizer chambers into the flue *a'*. It will thus be manifest that the gases flow in the opposite direction to the water and steam.

35 I claim:—

1. The combination with the smoke box of a horizontal smoke-tube boiler, of a system of superheater tubes and a system of economizer tubes, both of which are arranged 40 in a single transverse zone within said smoke box.

2. In combination with the smoke box of a horizontal smoke-tube boiler, smoke flues therein, the upper parts of said flues being 45 concentric with the boiler axis and extending vertically downward at their lower parts, superheater tubes in the upper part of said flues and economizer tubes in the lower part of said flues.

50 3. In combination with the smoke box of a horizontal smoke-tube boiler, smoke flues therein concentric at their upper parts with the boiler axis and open to the boiler end space, said smoke flues extending downwardly 55 below the plane of the boiler axis, superheater tubes arranged in said smoke flues, economizer flues disposed intermediate

the lower ends of said smoke flues, economizer tubes in said economizer flues, valves controlling communication between said smoke flues and the furnace gas draw-off space beneath the same, and valves controlling communication between said economizer flues and boiler end space.

4. In combination with the smoke box of a horizontal smoke-tube boiler, smoke flues therein concentric at their upper parts with the boiler axis and open to the boiler end space, said smoke flues extending downwardly below the plane of the boiler axis, superheater tubes arranged in said smoke flues, economizer flues disposed intermediate the lower ends of said smoke flues and having a space between them communicating with said boiler end space, economizer tubes in said economizer flues, valves controlling communication between said smoke flues and the furnace gas draw-off space beneath the same, valves controlling communication between said economizer flues and boiler end space, and a valve in the space between said economizer flues.

5. In combination with a horizontal smoke-tube boiler, a smoke box into the central part of which the smoke tubes open, an inner shell within the smoke box open above to form two side flues, a plurality of sinuous superheater tubes in the upper part of said flues and connected to the boiler and a plurality of sinuous feed water tubes in the lower part of said flues, said sinuous tubes winding from front to back of the smoke box.

6. In combination with a horizontal smoke tube boiler, a smoke box into the central part of which the smoke tubes open, a plurality of sinuous superheated tubes arranged on both sides of and within said smoke box, a plurality of sinuous feed water tubes subjacent to said superheater tubes, said sinuous tubes winding from front to back of the smoke box, a down-take flue beneath the smoke box and inner plates on the inside of said sinuous tubes forming flues within which said sinuous tubes are contained, said flues extending on both sides of said smoke box from the upper part thereof to said down-take flue.

In testimony whereof I have affixed my signature in presence of two witnesses.

FRANZ BÜRGER.
